UNITED STATES PATENT OFFICE.

FREDERICK SONNTAG, OF FORT ATKINSON, WISCONSIN.

PLUMB-LEVEL.

SPECIFICATION forming part of Letters Patent No. 361,728, dated April 26, 1887

Application filed February 1, 1886. Serial No. 190,425. (No model.)

To all whom it may concern:

Be it known that I, FREDERICK SONNTAG, a citizen of the United States, residing at Fort Atkinson, in the county of Jefferson and State 5 of Wisconsin, have invented a new and useful Plumb-Rule for Mechanical Use, of which the following is a specification.

My invention relates to improvements in plumbing-rules to be used in adjusting plumb-lines, angles, levels, &c., in which a pendulum-needle is used instead of a vial of spirits or cord and ball; and my object is, first, to provide against the action of the wind upon the mechanism; second, adapting it to adjustment for various angles with all the precision that a perpendicular line can be adjusted by the old "plumb line and ball," with no wind to disturb. I attain these objects by the mechanism illustrated in the accompanying drawings, in which—

Figure 1 is a side view of my plumb rule or staff. Fig. 2 is also a side view of the same with the cover B removed, showing the inside mechanism. Fig. 3 is a longitudinal section 25 of Fig. 1, cut at dotted line $x-x$. Fig. 4 is also a longitudinal section of the staff A, Fig. 1, except the pivot upon which the plumb-needle is hung, the change of which will be more fully explained hereinafter.

Similar letters refer to similar parts throughout the several views.

The rule or staff A is constructed of the best hard wood, three and one-half inches wide and one and one-half inches thick, dressed 35 straight, two and one-half feet long. One side is rabbeted to receive the cover B, rabbeted one-half an inch, leaving one-half an inch at each edge of the staff the full thickness, as shown in Figs. 1 and 2. The cover B is secured by screws e, as in Fig. 1. Both parts, A and B, are provided with countersunk holes E, as shown in all the figures.

In Fig. 2 the cap B is removed and a chamber, A', is then cut sufficiently large to provide 45 space for the lower end of the vertical plumb-needle C C', suspended upon pivot D, to swing

clear of the sides of the chamber A' until checked by the upper end coming into contact with the sides.

Fig. 4 shows the plumb-needle C" suspended 50 upon a pivot similar to that of the needle of a compass. The metal needle-rest D' is provided with a countersink, in which the point d rests. The needle is shown formed about the rest so as to balance itself and at the same 55 time prevent the point d from lifting out of the countersink D', and thereby secures it against any accidental displacement.

In Fig. 3 a glass, a a, is shown secured in the hole E of each piece A and B, and upon 60 the inner side of each glass is marked a scale, Figs. 1 and 2, to which the needle C C' points, to indicate the position of the staff A.

It will be observed that a "ball and line" is the oldest device known to be used for the 65 purpose of adjusting plumb lines, and still is acknowledged the most accurate principle known. It will also be observed that my weighted pendulum-needle embodies the same principle and accuracy, and is not liable to be 70 affected by the wind, nor liable to the breakage of a cord by an accidental fall.

I do not intend to claim, broadly, a weighted plumb-needle suspended in the chamber of a plumb-rule, it having been used prior to my 75 invention; but

What I do claim as my improvement, for which I desire to secure Letters Patent of the United States, is—

In combination with the plumb-stock A, 80 provided with a longitudinal chamber, A', circular aperture E in the sides, for exposing the upper end of needle C", the vertical weighted plumb-needle C", provided with a vertical pointed pivot, d, and a rest, D', with 85 the needle C" turned about it so as to balance upon the point of pivot d, substantially as and for the purpose set forth.

FREDERICK SONNTAG. [L. S.]
